US00D870416S

(12) **United States Design Patent** (10) **Patent No.:** **US D870,416 S**
(45) **Date of Patent:** **** Dec. 24, 2019**

(54) **PET TREAT**

(71) Applicant: **BIG HEART PET, INC.**, Orrville, OH (US)

(72) Inventors: **William T. Keehn**, Perry, KS (US); **Andrew Deakin**, Oakland, CA (US); **Judy Guo**, San Francisco, CA (US); **Molly Rolig**, Sonoma, CA (US); **Natalie Aronson**, Walnut Creek, CA (US); **Tammy Chung**, Milpitas, CA (US); **Jamie Lasser**, San Francisco, CA (US); **Zachary Parker Willard**, Akron, OH (US)

(73) Assignee: **BIG HEART PET, INC.**, Orrville, OH (US)

(**) Term: **15 Years**

(21) Appl. No.: **29/643,910**

(22) Filed: **Apr. 12, 2018**

(51) LOC (12) Cl. **01-01**

(52) U.S. Cl.

USPC **D1/199**

(57) **CLAIM**

The ornamental design of a pet treat, as shown and described.

DESCRIPTION

FIG. 1 is a top isometric view of a pet treat;

FIG. 2 is a bottom isometric view thereof;

FIG. 3 is a top plan view thereof;

FIG. 4 is a bottom plan view thereof;

FIG. 5 is a front elevation view thereof, wherein the rear elevation view is a mirror image thereof; and,

FIG. 6 is a left side elevation view thereof, wherein the right side elevation view is a mirror image thereof.

The broken lines in the figures are for the purpose of illustrating unclaimed portions of the pet treat and form no part of the claimed design.

1 Claim, 6 Drawing Sheets
